S. L. DRYFOOS.

POST CAP.

APPLICATION FILED MAR. 26, 1920.

1,355,657.

Patented Oct. 12, 1920.

FIG. 1.

FIG. 2.

FIG. 3.

FIG. 4.

FIG. 5.

FIG. 6.

Inventor,
Sidney L.
Dryfoos,

By *Albert L. Dryfoos* *Attorney*.

UNITED STATES PATENT OFFICE.

SIDNEY L. DRYFOOS, OF CLEVELAND, OHIO, ASSIGNOR TO THE DUPLEX HANGER COMPANY, OF CLEVELAND, OHIO, A CORPORATION OF OHIO.

POST-CAP.

1,355,657.

Specification of Letters Patent.

Patented Oct. 12, 1920.

Application filed March 26, 1920. Serial No. 368,917.

To all whom it may concern:

Be it known that I, SIDNEY L. DRYFOOS, a citizen of the United States of America, residing at Cleveland, in the county of 5 Cuyahoga and State of Ohio, have invented certain new and useful Improvements in Post-Caps, of which the following is a specification.

My invention relates to improvements in 10 post caps of the type adapted to be constructed of steel plate and has for its object the provision of a post cap which affords a greater initial and ultimate strength than is secured by any other like structure 15 of the same weight and cost of manufacture.

Another object of my invention is the avoidance of the expense for labor and the delay in preparing the end of the supporting post, which necessarily is involved by 20 the use of the well known and commonly used sheet metal post cap of the prior art, disclosed in the patent to Tuteur, No. 761,020, May 24th, 1904.

Referring to the structure therein set 25 forth, it is seen that the post cap comprises two flat side plates united by lateral bolts with an inverted U-shaped bearing plate. These bolts alone are depended upon in use, for transmitting the strain to the side plates 30 and said bolts, accordingly, are subjected to extreme shearing action. Moreover, the depending legs of the U-shaped bearing plate necessitate the shaping of the top of the supporting post by laterally cutting it 35 away sufficiently to accommodate said bearing plate, and this involves some expense, delay and a slight reduction in the cross section of the post or timber.

My invention contemplates the proper 40 shaping of the side plates so that the intermediate bearing plate is directly supported thereby edgewise throughout its length, independently of the connecting bolts or rivets, while the depending side portions 5 of said supporting plate are disposed in recesses formed in the side plates, so that they are flush with the major portions of the respective side plates, and shaping or trimming of the supporting post is completely eliminated.

The structural features of the post cap embodying my invention and its further advantages may be best explained by making

reference to the accompanying drawings, wherein:

Figure 1 is a view in elevation showing a 55 post cap of my invention with the supported girders and upper and lower posts in position, but adjacently broken away.

Fig. 2 is a vertical section on line 2—2 of 60 Fig. 1.

Fig. 3 and Fig. 5 respectively illustrate 65 in perspective, the disassembled side plates, while Fig. 4 similarly shows the associated supporting plate therefor.

Fig. 6 is a perspective view cut in vertical section illustrating the employment of 70 my improved post cap.

Throughout the several figures of the 75 drawings I have employed the same character of reference to indicate similar parts, but it should be noted that for purposes of illustration, the cross section of the sheet metal has been somewhat exaggerated as compared with the requirements of ordinary practice.

The several members of the post cap are 80 shown in Figs. 3, 4 and 5, comprising two side plates *a*, *b*, and an intermediate bearing member or supporting plate *c* of substantially U-shape, which is adapted to fit within the recesses of the side plates and receive support along its depending edges 85 throughout the lengths of the shoulders *a'*, *b'*. These side plates are readily cut, shaped and punched from steel plate, while the bearing member may be similarly formed or it may be fabricated from suitable structural shapes or channel members.

A plurality of transverse bolts *d* serve 90 to connect the members of the post cap in the well known manner, but with the depending legs of the channel or U-shaped bearing plate firmly clamped within the recessed side portions intermediately of the 95 side plates. It will be very readily understood that with the upper and lower posts *f*, *e*, inserted within the post cap, wherein they accurately fit, this bearing plate is substantially reinforced by the side plates 100 throughout their respective length, so that the bolts are relieved from excessive strain of the weight carried upon girders *g*, *h*. In consequence, the post cap of my invention may be made of less length than that of 105 the prior art, and still afford equal support

for the timbers and the load carried thereby.

With the cited post cap of the prior art the necessity for framing and fitting the supporting post *e* is apparent. This involves unnecessary expense for labor and an appreciable reduction in the cross section of the upper end of said post. Thus, in erecting the building, the posts *e*, *f* may be inserted in place without framing, and held in their assembled relation by lag screws *i*, before placing said posts in position within the structure. This materially advances building operations, with a reduction in the cost of labor, when my improved post cap is used.

It will be appreciated that practically the same advantages are present in the use of this post cap in inverted relation, *i. e.*, with the legs of the U-shaped bearing member positioned above the level of said plate, and I have employed the terms herein and in the appended claims relatively, merely as descriptive of the preferred position of the post cap.

In order to afford additional initial support for the engaging edges of the bearing member, I may also insert rivets *j* to supplement the bolts *d*; these serving to clamp the depending edges of the bearing member securely within the supporting recesses, preferably adjacent to the extremities thereof. Under ordinary conditions, however, a plurality of bolts, which insure more ready assemblage of the post cap, are all that are required for connecting the respective members thereof.

Having now described the improved post cap of my invention, I claim as new and desire to secure by Letters Patent, the following:

1. A post cap constructed from steel plate, comprising a U-shaped bearing member, two steel side plates respectively offset intermediately to accommodate the lateral portions of said bearing member and afford

support therefor, and means for uniting said side plates and bearing member, substantially as set forth.

2. A post cap formed from steel plate members, comprising a bearing member having its side portions downwardly extending at right angles to the body thereof, side plates intermediately offset above and below the downturned side portions of said bearing member sufficiently to accommodate the same and afford a flush receptacle or cap for the supporting post, and means for uniting said bearing member and side plates, substantially as set forth. 60

3. A post cap formed from steel plate members, comprising a bearing plate rectangularly bent downward along both edges to the dimensions of the supporting post and substantially throughout its entire 65 length, two side plates intermediately offset to accommodate the downturned edges of the bearing plate and positioned to support the same throughout their lengths, and means for uniting said edges and side plates 70 whereby the bearing plate is reinforced, substantially as set forth.

4. A post cap comprising two steel plate sides intermediately offset to form supporting shoulders, a bearing member positioned 75 therebetween and supported by said shoulders, and means for gripping said member between the side plates and thereby connecting the several members of said post cap, substantially as set forth. 80

5. A post cap comprising two steel plate sides intermediately shaped to form recesses affording supporting shoulders above and below, and a substantially U-shaped bearing member inserted between said side plates 85 with its legs flush with the side walls, and transverse bolts uniting said side plates and securing the bearing member within their recesses, substantially as set forth.

In testimony whereof I do now affix my 90 signature.

SIDNEY L. DRYFOOS.
